Fig. 12

Fig. 9

Figure 1 is a top plan view of an exposure meter showing our new design;

Figure 2 is a bottom plan view thereof with the light amplifier open and the light sensitivity attachment in place;

Figure 3 a right side elevational view thereof with the parts disposed as in Fig. 2;

Figure 4 is a bottom plan view thereof with the light amplifier closed and the light sensitivity attachment in place;

Figure 5 is a right side elevational view thereof with the parts disposed as in Fig. 4;

Figure 6 is a front elevational view thereof with the parts disposed as in Fig. 4;

Figure 7 is a front elevational view thereof with the parts disposed as in Fig. 2;

Figure 8 is a rear elevational view thereof with the light amplifier open;

Figure 9 is a left side elevational view thereof with the parts disposed as in Fig. 2;

Figure 10 is a bottom plan view thereof with the light amplifier closed and with the light sensitivity attachment removed from the meter;

Fig. 11 is a front elevational view thereof with the light amplifier closed, a secondary light amplifier open, and the light sensitivity attachment removed from the meter; and

Figure 12 is a right side elevational view thereof with the parts disposed as in Fig. 10.

The dominant features of the design reside in the portions shown in full lines.

We claim:

The ornamental design for an exposure meter, as shown and described.
